Primary Examiner — Joseph Kukella*Assistant Examiner* — Lavon M. Amerson(74) *Attorney, Agent, or Firm* — Suzanne Kikel, Patent Agent(57) **CLAIM**

The ornamental design for a windshield wiper cover, as shown and described.

DESCRIPTION

FIG. 1 is a front perspective view of a windshield wiper cover, showing my new design;
 FIG. 2 is a front view thereof;
 FIG. 3 is a rear view thereof;
 FIG. 4 is a top plan view thereof;
 FIG. 5 is a bottom plan view thereof;
 FIG. 6 is a right-side view thereof;
 FIG. 7 is a left side view thereof; and,
 FIG. 8 is a front perspective view thereof arranged on a windshield wiper and in smaller scale thereof.
 In the drawings, the broken lines depicting a windshield wiper form no part of the claimed design. In the drawings, the stylized triangle with the words wizzard wiper covers, and the stylized stars is an unregistered mark and is owned by the inventor.
